Edwin Ball Stimpson
By his Attorney
Abel L. Brownrigg

UNITED STATES PATENT OFFICE.

EDWIN BALL STIMPSON, OF BROOKLYN, NEW YORK.

CARTRIDGE-BELT.

1,288,264.

Specification of Letters Patent. Patented Dec. 17, 1918.

Application filed June 21, 1918. Serial No. 241,269.

To all whom it may concern:

Be it known that I, EDWIN BALL STIMPSON, a citizen of the United States, residing at Brooklyn, county of Kings, and State of New York, have invented certain new and useful Improvements in Cartridge-Belts, of which the following is a specification.

This invention relates generally to machine gun cartridge feeding belts.

In application Ser. No. 233,553, filed May 9, 1918, and application Ser. No. 234,542, filed May 14, 1918, cartridge belts formed of layers of paper and attached together by means of metallic fastening means taking various forms are shown and described. The layers or strips of paper thus made use of to form a belt are brought into direct contact at the points where they are held together between the spaces reserved to provide the cartridge holding loops. It has been found that, if the strip members can be arranged in a spaced apart relation with respect to each other, the sharp angular bends produced in the strips by the presence of the cartridges in the loops is much less pronounced and, in addition, the insertion of the cartridges into their places in the loops is greatly facilitated.

The principal object of the present invention is accordingly to provide a cartridge belt of this general type in which the folds or layers thereof will be separated from each other for the purposes indicated.

With this and other objects in view, the main feature of the invention resides in the provision of a cartridge belt formed of layers of material such as paper, attached together at suitable intervals to form cartridge holding loops, and in interposing between the layers at the points of attachment spacing members for holding the loop forming strips in a spaced apart relation with respect to one another.

Other features of the invention will be hereinafter referred to.

In the accompanying drawing, in which a number of embodiments of the invention are illustrated,

Figure 1 is a face view partly broken away, of a section of belt embodying a preferred form of the invention.

Fig. 2 is a sectional view taken along the line 2-2 of Fig. 1.

Fig. 3 is a face view of a section of belt showing another form of the invention.

Fig. 4 is a face view of an enlarged section of belt showing the use of still another form of the invention and showing another form of fastening means.

Fig. 5 is a face view of an enlarged section of belt showing still another form of fastening means.

Fig. 6 is a view in perspective of a preferred form of spacing member for use in the device.

In Fig. 1 of the drawing there is shown a partly broken away section of cartridge belt embodying the invention, in which two strips of flexible sheet material 1 and 3, such as paper or fabric, have interposed between them at suitable intervals to form cartridge holding loops, separating or spacing members 5 having a substantial thickness as indicated in Figs. 2 and 6. In the form of the invention shown in Fig. 1, the strips or layers 1 and 3 are attached to the intervening spacing members and to each other by means of the eyelets 5, one of which is placed in position near each end of the spacing member, and correspondingly near one of the lateral edges of the strips.

The spacing members are preferably formed from cardboard and are so shaped that their opposite edges follow the contour of the adjacent cartridges when they are placed in position as in Fig. 1. By reference to Fig. 2 it will be seen that the strip members 1 and 3 forming the sides of the belt are spaced apart from each other even when there are no cartridges in the loops, so that the operation of inserting the needle of the loading machine between the belt strips in each loop is greatly facilitated.

Still another function secured by the use of the spacing members is that of so stiffening the belt that it will not coil up laterally and interfere with the loading operation as well as with subsequent handling. A still more important use of the spacing members resides, however, in their tendency to decrease the amount of lateral deflection of the belt strips that is required to form the cartridge holding loops 11, as is indicated in Fig. 2 of the drawing. It will also be noted in this figure that opposite edges of the spacing members are directly engaged by the car-

tridges, so that the members share in the support of the cartridges and prevent a pinching action between the cartridge and eyelet flange that would be likely to injure 5 the belt strip.

In the modification of the invention shown in Fig. 3 the strip members 1 and 3 are preferably themselves formed of thin layers of material, such as paper, provided with 10 reinforcing cords 11 placed in pairs along either edge, as in one of the prior applications already referred to. It will be seen that a very secure construction is provided in this form of the invention by causing the 15 flanges of the eyelets 7 to overlie the cord members 13 in the manner indicated.

In Fig. 4 of the drawing there is shown a modification very similar to that shown in Fig. 3, except that staples 15 are used 20 instead of eyelets for attaching the strip members 1 and 3 to the intervening spacing members 5. It will be noted that the staples 15 are of such length as to include both reinforcing cords to thereby provide a very 25 efficient construction that will withstand any strain to which it is likely to be subjected. Still another form of fastening means is shown in Fig. 5, in which metal clips 17 and 19 are made use of for attaching the cords 30 13 and strips together. It will be noted that the clips 19 along one edge of the belt are wider than the clips 17 at the other in order to accommodate themselves to the widened spaces formed by the correspond- 35 ingly narrowed portions of the cartridges. While the reinforcing cords 13 are shown as uncovered, it is of course obvious that they may be covered with a sheet of material, as in Fig. 3, preferably of thin material.

40 Having thus described my invention, what I claim and desire to secure by Letters Patent of the United States is:

1. A cartridge belt comprising: strips of paper attached together at suitable intervals along their length to form cartridge holding loops, and strip spacing members interposed between said layers at said points of attachment, said spacing members being arranged to normally hold said loops in a 50 partly opened condition.

2. A cartridge belt comprising: strips of longitudinally reinforced paper placed in face to face relation, strip spacing members interposed between said strips at suitable intervals along their length to form cartridge holding loops, said spacing members being arranged to normally hold said loops in a partly opened condition and fastening members arranged to attach said strips to the 60 intervening spacing members.

3. A cartridge belt comprising: strips of longitudinally reinforced paper placed in face to face relation, strip spacing members interposed between said strips at suitable intervals along their length to form cartridge

holding loops, said spacing members being arranged to normally hold said loops in a partly opened condition and metallic fastening members arranged to clamp said strips to the intervening spacing members and to 70 each other.

4. A cartridge belt comprising: strips of longitudinally reinforced paper placed in face to face relation, strip spacing members interposed between said strips at suitable 75 intervals along their length to form cartridge holding loops, said spacing members being arranged to normally hold said loops in a partly opened condition and metallic fastening members arranged to attach said strips to the intervening spacing members, said fastening members having less width than the width of said spacing members, whereby the cartridges will be directly engaged and supported by said spacing members. 85

5. A cartridge belt comprising: strips of longitudinally reinforced paper, strip spacing members of substantial thickness arranged transversely to said strips at suitable intervals to form cartridge holding loops and adapted to normally hold said loops in a partly opened condition, and means for attaching the strips to the intervening spacing members. 95

6. A cartridge belt comprising: strips of longitudinally reinforced paper arranged in a face to face relation, strip spacing members of substantial thickness interposed between said strips and arranged transversely 100 thereto at suitable intervals to form cartridge holding loops and adapted to normally hold said loops in a partly opened condition, said spacing members being wider at one end than the other to thereby conform to the reduced diameter of one end of the cartridges, and means for attaching the strips to the intervening spacing members. 105

7. A cartridge belt comprising: layers of reinforced paper attached together at suitable intervals along their length to form cartridge holding loops, and spacing members interposed between said layers at said points of attachment, said spacing members being arranged to normally hold said loops 115 in a partly opened condition.

8. A cartridge belt comprising: strips of paper having longitudinally arranged reinforcing cords attached thereto, strip spacing members interposed between said strips 120 and arranged transversely thereto at suitable intervals to form cartridge holding loops, said spacing members being arranged to normally hold said loops in a partly opened condition, and means for attaching 125 the strips to the intervening spacing members along the reinforced portions.

9. A cartridge belt comprising: strips of paper placed in face to face relation and having reinforcing tensile members attached 130

thereto, spacing members of substantial thickness interposed between said strips at suitable intervals along their length to form cartridge holding loops, said spacing members being wider at one end than the other, and metallic fastening members arranged to

attach said strips to the intervening spacing members along the reinforced portions.

Signed at Brooklyn, in the county of Kings, and State of New York, this 14th day of June, 1918.

EDWIN BALL STIMPSON.
